UNITED STATES PATENT OFFICE

EDWARD E. ROSE, OF CICERO, ILLINOIS

METALLIC DOORFRAME

Application filed December 4, 1929. Serial No. 411,550.

My invention relates to sheet metal door frames and more particularly to improvements in such frames designed to facilitate the application of the door hardware and involving a wood insert or jamb piece, and my main object is to lend the door frame such a formation as to firmly secure the jamb piece in place.

A further object of the invention is to so 10 design the novel door frame that a metal insert or jamb piece may be applied where maximum fire protection is desired.

A still further object of the invention is to construct the novel door frame on lines of 15 extreme simplicity and rigidity.

With the above objects in view and any others that may suggest themselves from the specification and claims to follow, a better 20 understanding of the invention may be had by reference to the accompanying drawings, in which—

Figure 1 is an elevation of a typical door 25 installation, showing the door frame;

Fig. 2 is a perspective view on a magnified scale of a portion of the post section of the door frame, showing the application of my 30 wooden insert or jamb piece;

Fig. 3 is a section on the line 3—3 of Figure 1, on an enlarged scale;

35 Fig. 4 is a section similar to that of Figure 3, but illustrating the application of my metallic insert or jamb piece;

Fig. 5 is an elevation, showing the prevalent 40 type of support for the frame hardware; and

Figs. 6 and 7, are respectively, sections on the lines 6—6 and 7—7 of Figure 5.

While the metal door frame art has developed 45 various methods of adapting the door frame to different hardware specifications, such as by the use of insert jamb pieces and sectional elements designed to receive the hardware, the prevalent practice is still to have the frame entirely manufactured to 50 specifications including those of the hardware. Thus, with frequent unavoidable variations in the height of strike or hinge plates or differences in the thickness thereof, the factory producing the frame embodies errors therein which require extra labor at the

site of installation for rectification. Commonly, a frame post appears as in Figure 5, being cut out with an opening 10 where the hinge or strike plate is applicable. In back of this opening, the post receives a metallic 55 plate 11 which is bulged as indicated at 11a in Figure 7 in an inward direction to suit the thickness of a hinge or strike plate whereby to locate the same flush with the face of the post. In addition, the plate 11 is made with 60 perforations 11b to suit the hinge or strike plate holes. To repeat, it is easily apparent that slight errors in the specifications as sent to the factory will be reflected in the product as delivered and attended by more 65 or less loss of time and energy.

In the metal door frame art various inserts have been devised for application to the metallic door frame, such inserts usually being of wood and susceptible to modification at the site of delivery for the proper fitting of the hinge or strike plates. In my main embodiment, 12 denotes the frontal section of the sheet metal door frame post or door-buck, as the latter is called in the trade, 70 the sides being denoted at 13 and the inner ends at 14, these being of hooked formation in order to exercise a locking engagement with the tile or other wall in which the door frame is built. The section 12 is formed by 75 an inward bend 15 made from the door stop 16, said bend having a lateral return section 17 and a continuation 18 to meet the section 12 at right angles from one side. On the opposite side, the section is made with an 80 outward bend 19 at right angles which extends with a further right angled bend 20, terminating with the latter. This bend is clinched by the channeled section 21 of a facing 22 which forms a lateral bend of the 85 corresponding post side 13.

The parts described above as occurring between the stop bend 15 and the corresponding post side 13 form a channel or pocket for a vertical wood strip 23, this strip extending 90 the full height of the post and being finished to match the same. As apparent from Figure 2, this strip offers its entire outer surface for the application of a hinge or strike plate, as suggested in Figure 3 in the manner 100

of any frame post made of wood. The illustration also indicates a cavity 23a cut in the surface of the wood strip or insert for the sinking of the hinge or strike plate to the desired depth. Thus, the frame can be constructed at the factory to include the wood facing and without the need of any door hardware specifications, the hardware being applied in the ordinary way at the site of installation.

While the wood facing in the door frame is not essentially novel, it will be noted that the facing in my case is particularly constructed and retained. The strip 23, while of generally oblong cross section to fit the channel in which it seats, is also cut in the outer side edge with a deep groove 24 in which is lodged the doubled joint of the channel and side 23, as formed by parts 21 and 22. The wood strip 23 not only seats in the channel, but is locked in two places, first by the section 17 and by the joint just mentioned, which is in the form of a tongue seating in the groove 24. With the parts accurately made and fitted at the factory, it will be appreciated that the strip 23 is virtually an integral part of the post or door buck, and finds in the latter a firm and durable support. Also, being of full height, the strip or insert cannot sag or shift from the weight of the door.

The above installation is suitable in most instances where metallic door frames are desirable and not specified as fully fireproof. However, in the latter case, not only are the door frames specified as fireproof but even the doors are metal, so that the wood insert 23 would fail of approval. To suit fully fireproof installations, I have designed a modification of the insert described, comprising of a full-height facing of metal. As shown in Figure 4, this facing follows the general outer contour of the wood facing, but has no inner side. Thus, the modified facing comprises a frontal section 25, an inward bend 26 at one side and applied within the frame section 17, a short inward bend 27 to meet the side 13, a lateral channel 28 from the bend 27 to engage the locking tongue 20, 21, 22, and a final short inward bend 29 extending to the internal facing 12. In this installation, the insert facing would necessarily have to be made at the factory to specifications including those for the strike and hinge plates. However, in case of error developing in the production of the inserts, whereby difficulty or waste results only the insert is risked and not the entire frame post. Thus, the latter may be kept in stock and inserts made up with dispatch to specifications.

It will be seen that in the main and modified embodiments I have fitted the insert firmly and durably into the frame post by a particular locking arrangement. Yet, no

special parts or fastening elements are used, and no difficulty or hardship is presented to the factory for the formation of the assembly. In fact, the ultimate economy by producing the frame with the improved features will more than offset the cost of any equipment necessitated by the change from the prevalent design.

I claim:

1. A jamb facing comprising a column having sides and a front, an offset portion of the front constituting a door stop, a recessed section extending away from said door stop and defining a pocket having a key, and a facing member lodged in the pocket and locked by the key.

2. A jamb facing comprising a column having its front offset to form a door stop, a section of the front extending away from the door stop to define a pocket, a facing member seated in the pocket, and cooperating means in the pocket and facing member for locking the latter in place.

3. A jamb column having its front offset to form a door stop, a section of the front offset in a direction reverse from the stop, a facing member seated in the section and means for locking the member in position.

4. A jamb facing comprising a section frontally recessed, said recess defining a seat substantially rectangular in cross section, a flange extending within the seat, a facing member having a slot medially therethru, said member lodged in the seat thru the locking engagement of the flange and slot.

In testimony whereof I affix my signature.
EDWARD E. ROSE.
